UNITED STATES PATENT OFFICE.

HOWARD LUTHER WHITELEY, OF LOWELL, MASSACHUSETTS.

HOOK HOLD.

1,402,330.

Specification of Letters Patent.

Patented Jan. 3, 1922.

Application filed October 29, 1919. Serial No. 334,305.

To all whom it may concern:

Be it known that I, HOWARD L. WHITELEY, a citizen of the United States, residing at Lowell, in the county of Middlesex and State 5 of Massachusetts, have invented certain new and useful Improvements in Hook Holds; and I do hereby declare the following to be a full, clear, and exact description of the invention, such as will enable others skilled 10 in the art to which it appertains to make and use the same.

The present invention relates to hook-holds. The object of the invention is to produce a hook-hold for use on bales and 15 rolls of material liable to be injured by the use of the bale-hook. The invention consists in a hook-hold adapted to be secured to a bale or package by the hoops or ropes or wires used on the bale and provided with a 20 projecting portion adapted to be engaged by the bale-hook. To the above end the present invention consists in the hook-hold hereinafter described and particularly defined in the claims.

25 In the accompanying drawings illustrating the preferred form of the invention, Fig. 1 is a side elevation; Fig. 2 is a front elevation; Fig. 3 is a perspective view of the preferred form of the hook-hold hereinafter described; Fig. 4 is a view of a bale showing the hook-hold in place on the bale illustrating its mode of use.

The illustrated embodiment of the invention is described as follows: The body 1 of 35 the hook-hold consists of a piece of sheet iron. This is provided with a longitudinal groove 2 to receive the bale strap or hoop. At each end of the body of the hook-hold it is pierced to form an eye 3 through which 40 the bale hoop or strap is passed. At the center of the body 1 a hook loop or eye 4 is provided. This hook loop 4 is stamped up from the body 1 as shown in Figs. 1 and 2, being arched from side to side, the arch 45 having flaring mouths 5 at each end adapted to receive the bale-hook. The groove 2 receives the bale strap or hoop, holds the hook-hold in place and at the same time

affords a groove to guide the point of the bale-hook into the hook-loop 4.

50 The present invention may be embodied in many different forms and may be made of any suitable material. In its broader aspects it comprises a hook-loop or eye adapted to receive the bale-hook and means 55 for holding the hook-loop or eye on the package. As many hook-holds may be used on each package as is demanded by its size, weight, etc.

The injury to expensive goods baled for 60 shipment by the bale-hook is in the aggregate very large. The injury to baled cotton goods by bale-hooks would, in a single year, amount to hundreds of thousands of dollars in the United States alone, a loss which has 65 thrown a heavy burden upon the transportation companies. The use of the hook-hold of this invention will entirely eliminate or largely reduce this loss.

Having thus described the invention, what 70 is claimed is:

1. A hook-hold for shipping packages comprising a hook-loop to receive a bale-hook and means for holding the hook-loop on the package.

75 2. A hook-hold for shipping packages comprising a hook-loop to receive a bale-hook and a body portion by which the hook-loop is adapted to be secured to the package, such body portion being pierced to receive 80 the bale strap or hoop.

3. A hook-hold for shipping packages comprising a hook-loop to receive a bale-hook and a body portion provided with a hook guiding groove directed toward the eye 85 of the loop for guiding a bale-hook point to the hook-loop.

4. A hook-hold for shipping packages comprising a body portion consisting of a piece of sheet iron having a longitudinal 90 groove adapted to receive the bale-hoop or strap and having a hook-loop or eye stamped up from the body portion for engagement by a bale-hook.

HOWARD LUTHER WHITELEY.
